LIFESAVING APPLIANCE

Marco Aurelio Antognazzi, Rosario de Santa Fe,
ArgentinaApplication April 16, 1937, Serial No. 137,345. Re-
newed September 21, 1938. In Argentina Jan-
uary 20, 1937

1 Claim. (Cl. 9—19)

The present invention relates to life-saving appliances of the kind which may be carried upon the person as for example when bathing, and has for its object the provision of a simple, compact and efficient device which may, if desired, be incorporated in or permanently or detachably secured to a bathing dress, means being provided in the device whereby the wearer may, by a simple manual operation render the device effective to give sufficient support to prevent the wearer from drowning in the event of exhaustion or cramp occurring.

Another object of the invention is to provide a life-saving appliance comprising an expansible pneumatic chamber in communication with a source of gas for inflating said chamber, said source being provided with means operable from without to cause gas to flow from said source to said chamber and inflate the latter to a sufficient degree to keep the wearer of the device afloat with his head above water.

A further object of the invention is to provide a life-saving appliance comprising an inflatable pneumatic chamber, a source of inflating gas communicating with said chamber and means actuatable from without in order normally to interrupt said communication, said pneumatic chamber being constructed to form a part—for example the shoulder-straps or belt—of a bathing costume and said source being of such dimensions and weight as to enable it to be secured to the costume without incommoding the wearer.

A further object of the invention is to provide a life-saving device comprising an inflatable pneumatic chamber adapted to be worn on the person and communicating with a container containing a gas under pressure the communication between said chamber and said container being effected by means of a closed passage-way having a lateral opening into which the mouth of the container is adapted to protrude, means being provided in said passage-way for piercing the seal of the container and further means operable from without being provided for moving said container towards said seal-piercing means.

Still another object of the present invention is to provide a life-saving appliance of the kind hereinbefore described in which the source of gas is constituted by a receptacle having two compartments containing separately chemical reagents which, when mixed, will readily give off a sufficient quantity of gas, said compartments being separated by a partition wall comprising a normally closed valve means and one of said compartments being formed at least in part of

resilient material so that under sufficient external pressure it may collapse, without breaking and thereby cause said valve to unseat to permit said reagents to mix.

Another object of the present invention is to provide a life-saving device of the type just described in which, however, both compartments have substantially rigid walls and one of said compartments is provided with spring-controlled means operable from without to effect unseating of the valve in the partition wall.

In the drawings:

Fig. 1 is a longitudinal section of one of the preferred forms of the source of gas showing its connection to the pneumatic chamber.

Fig. 2 is a section similar to that of Fig. 1 of an alternative form of the source of gas.

Fig. 3 is a longitudinal section of a further modification of the source of gas.

Fig. 4 is a diagrammatic representation of the complete life-saving appliance designed as a belt, and

Figs. 5 and 6 are illustrations of the device incorporated in bathing costumes.

With particular reference to Figs. 1, 4 and 6 my novel life-saving device comprises an inflatable pneumatic chamber 10 which may take the form of a belt as shown in Fig. 4 or of a belt and shoulder-straps as shown in Figs. 5 and 6, said chamber being made of some elastic material as, for example, vulcanized rubber, which may if desired be covered with fabric, as for example when said chamber is incorporated in the bathing costume. At one or more points there is attached to said chamber by a leak-proof connection such as that shown at 12 in the drawings, a source 14 of gas which, in the embodiment shown in Fig. 1, consists of a bottle 16 of the type used for containing gas under pressure, said bottle being surrounded by a protective casing 18 and having a seal 20 fitted in its neck.

The upper end of the casing 18, i. e. the end at which the mouth of the bottle is located is hermetically closed by means of an end cover 22 having a depending flange 23 and an internal partition 26 between which and the end wall 24 there is formed a passage-way 28 which communicates directly with the bore 30 of the main member 12 of the connection to the pneumatic chamber 10, the female member of said connection being preferably formed by a laterally projecting boss 32 of the end cover 22. The partition 26 is centrally perforated to receive the neck of the bottle 16 and thus provides a lateral opening 27 communicating with said passage-way 28.

The partition 26 comprises a rubber portion 29 intended to grip firmly the neck of the bottle 16 while allowing of a certain amount of axial movement.

- 5 Opposite the lateral opening 29 there is secured to the end-wall 24 a seal-piercer 34, and the lower end of the casing 18 carries a plunger or push-button device 31 upon which the bottom of the bottle 16 is adapted to rest. The device is
- 10 assembled by pushing the neck of the charged and sealed bottle 16 into the opening 29 until the seal just comes into contact with the piercer 34, whereupon the casing 18 is screwed into the flange 23. In case of danger, the wearer need
- 15 only press up the button 31 until the piercer 34 has perforated the seal, whereupon the gaseous contents of the bottle will escape through the broken seal into passage 28 and thence through bore 30 into the pneumatic chamber 10 which
- 20 will thus be inflated.

In Fig. 2 there is shown an alternative form of the appliance which as illustrated consists of a container 16a divided into two compartments by a partition wall 36. The upper compartment 38 is adapted to be screwed into the flange 23 of the end cover 22a which in this instance carries no seal-piercer but is internally recessed to receive a filter plate 40. The other end of the compartment 38 carries the second compartment 42 which in this embodiment is formed by a bulb of rubber or the like material suitably secured to the end of compartment 38.

From the partition wall 36 which has a central perforation 44 there extends upwardly into compartment 38 a perforated conduit 46, the end of which adjacent the partition wall is enlarged to accommodate a spring 48 which normally urges a closure plate 50 against said partition wall 36 to cover said central perforation 34.

- 40 The two compartments are filled separately with chemical substances which, when brought into contact will readily give off considerable volumes of gas. Thus for example, compartment 38 may be filled with calcium carbide as indicated at 52 in which event compartment 42 will be filled with water as shown at 54. Upon compressing the bulb of compartment 42 the water will lift plate 50 against the action of spring 48 and will penetrate by way of conduit 46 into compartment 38 in which the well-known reaction will take place whereby acetylene gas is given off. This gas passes upwardly through the filter

plate 40 into the passage-way 28 and thence into the pneumatic chamber 10. The purpose of the filter plate is to prevent the entrance into the pneumatic chamber 30 of any spray or fine particles of water which may be carried up by the 5 gas.

In the embodiment shown in Fig. 3 the lower compartment 42a is formed by a prolongation of the rigid wall of the compartment 16a below the partition wall 36, and is hermetically closed by 10 an end-cap 56 which carries centrally a push-button 58 between which and the partition wall 36 a compression spring 60 is located. The push-button comprises a plunger 62 which is a piston fit in the compartment 42a. The spring 60 normally holds the push-button and the plunger in their position furthest from the partition wall 36 and thus a space is provided to contain the second reagent 54. Upon depressing the push-button the plunger 62 exerts pressure on the 20 liquid reagent 54 and thus on closure plate 50 which will as before be unseated so as to allow the liquid reagent to enter the upper compartment.

I claim:

A life-saving appliance of the type described comprising a pneumatic chamber, an end cover having a depending flange, a transverse gas-permeable partition in said end cover and spaced from the end-wall thereof to define a passage-way, a hermetic coupling connecting said end cover to said chamber and comprising a duct communicating with said passage-way, a container detachably secured to said depending flange, a partition wall dividing said container into upper and lower compartments, an opening in said partition wall, a perforated conduit located over said opening and extending from said partition wall into said upper compartment, said conduit having its end adjacent said partition 40 wall enlarged, a closure plate normally covering said opening and pressed against said partition wall by a spring housed in said enlarged end, said container having a rigid wall on the same side of the partition wall as said conduit and an 45 elastic wall on the other side of said partition wall and containing separately in the upper and lower compartments chemical reagents which when mixed with evolve a sufficient amount of gas to inflate said pneumatic chamber.
